UNITED STATES PATENT OFFICE.

EVERETT K. BRAY AND ROBERT H. SEEGAR, OF OCOEE, FLORIDA.

WHIFFLETREE-HOOK.

SPECIFICATION forming part of Letters Patent No. 720,556, dated February 17, 1903.

Application filed December 5, 1902. Serial No. 134,041. (No model.)

To all whom it may concern:

Be it known that we, EVERETT K. BRAY and ROBERT H. SEEGAR, citizens of the United States, residing at Ocoee, in the county of Orange and State of Florida, have invented a new and useful Whiffletree-Hook, of which the following is a specification.

Our invention relates to improvements in whiffletree-hooks; and it consists in the peculiar construction and combination of parts more specifically set forth hereinafter and particularly pointed out in the claims.

The object of our invention is to provide a hook with which a trace can be quickly and conveniently engaged and from which it may be as quickly and conveniently disengaged, when desired, accidental disengagement of such trace being prevented, and, further, to guard against the accidental hooking or catching of the reins therein, the hook being thoroughly reliable under all circumstances and conditions and not readily injured.

In the accompanying drawings, Figure 1 is a perspective view of a hook embodying the invention. Fig. 2 is a side elevation of the same. Fig. 3 is a bottom plan view of the hook when in normal position.

A represents the whiffletree; B, a clamp or clip secured thereto by screw C.

D is a hook hung loosely by eye y in eye x of clip B, an intermediate portion of the shank being enlarged and perforated to form a guide K, extending diagonally therethrough.

F is the feature of our invention and consists of a pin, as shown, having on its outer end a head G and on its inner end another but smaller head H, which is upset or formed thereon after pin G is in position in guide K and is just large enough to prevent pin G from being displaced. The pin is seated loosely in guide K, which extends diagonally through the enlargement in the shank of hook D, as shown, in such position that the end H when in normal position coincides with the end E of hook D, but adapted to slide in hole K by gravity to assume the dotted-line position when hook D is raised to a vertical or nearly vertical position.

The operation of the device is as follows: When it is desired to engage a trace therein, the hook D is raised to a vertical or nearly

vertical position, whereupon the pin G by its own weight slides to dotted-line or open position, thereby allowing the eye of the trace to pass freely over the end E of the hook, 55 and when the latter is released and drops to its normal position pin G slides through guide K and head H comes in contact with end E of hook D, thereby closing the throat of the hook and preventing the trace from 60 accidentally becoming disengaged or the reins from becoming caught therein. When it is desired to release the trace, the above-described operation is reversed.

The outer head with which the throat-closing pin is provided may be of a diameter slightly in excess of the thickness or width of the shank of the hook at that point in order to form a suitable grip for withdrawing the pin from its locking position when this operation should be found more convenient than tilting or raising the hook.

It is obvious that any form of connection having an eye therein to engage eye y of hook D may be substituted for clip B, and we are 75 aware that clips substantially in the form here shown have heretofore been manufactured, and we therefore claim clip B as no part of our invention and limit ourselves to no particular form of device for attaching 80 our hook to a whiffletree. We are further aware that hooks for whiffletrees have heretofore been made very similar in form to hook D and that hooks have been made in various forms with means actuated by spring and 85 links and attached by hinges for the purpose of closing in some manner the throat thereof; but we are not aware that a hook has been made with a pin longitudinally slidable therein by gravity, which construction by the absence of springs and hinges and its extreme 90 simplicity is not liable to get out of order and is both convenient and reliable in operation.

Having thus described our invention, what we claim is—

1. A whiffletree-hook having a shank provided with a guide in alinement with the extremity of the hook, and a gravity-closing pin mounted in said guide.
2. A whiffletree-hook having a shank provided with a guide in alinement with the extremity of the hook, and a gravity-actuated

throat-closing pin fitted in said guide and headed at its extremities to prevent displacement thereof.

3. A whiffletree-hook having a shank provided with a guide in alinement with the extremity of the hook, and a throat-closing pin mounted in said guide and having its outer end provided with a grip projecting beyond the lateral surfaces of the shank.

In testimony that we claim the foregoing as our own we have hereto affixed our signatures in the presence of two witnesses.

EVERETT K. BRAY.
ROBERT H. SEEGAR.
